DESIGN FOR AN APRON

Abraham N. Spánel, Dover, Del.

Application June 11, 1938, Serial No. 77,775

Term of patent 14 years

To all whom it may concern:

Be it known that I, Abraham N. Spánel, a citizen of the United States, residing at Dover, in the county of Kent and State of Delaware, have invented a new, original, and ornamental Design for an Apron, of which the following is a specification, reference being had to the accompanying drawing, forming part thereof.

The figure is a plan view of an apron showing my new design.

The design comprises an apron having a bib portion with a neck opening of the specific configuration shown.

I claim:

The ornamental design for an apron, substantially as shown and described.

ABRAHAM N. SPÁNEL.
